UNITED STATES PATENT OFFICE.

ADOLF H. SCHAFFERT, OF ROCHESTER, NEW YORK, ASSIGNOR TO YAWMAN & ERBE
MANUFACTURING CO., OF ROCHESTER, NEW YORK, A CORPORATION OF NEW YORK.

FILE FOLDER.

Application filed January 15, 1923. Serial No. 612,611.

This invention relates to improvements in folders, particularly of the type which are made to be filed vertically.

The object of the invention is the provision of an improved folder in which means are provided for so confining the papers placed within the folder that they will be prevented from working up above the edge of the forward portion of the folder, and thus giving the file a mussy appearance and obscuring the filing legend carried by the back portion of the folder.

The principal feature of the invention is the provision of a flap secured to the back portion of the folder, which is adapted to be folded down between the front and back portions of the folder and overlie the contents.

It is believed the invention will be readily understood from a description thereof taken in connection with the accompanying drawings, in which—

Figure 1 is a perspective view of one form of the device, and

Figure 2 is a similar view of a modified form of folder.

Referring now to the drawings, 10 indicates the front side or cover of the folder, and 11 the rear side. The folder between the parts 10 and 11 is scored or creased, as indicated at 12 and 13, to facilitate forming the folder with the bottom portion 14. When only a few papers are confined within the folder, the folder need be creased along only one of the scorings, as 13. The upper edge of the rear side or portion 11 is provided with a filing tab 15 upon which may be written the usual filing legend. The filing tabs 15 may appear at any point along the upper edge of the file to suit the requirements of the filing system employed.

Pasted, or otherwise secured, to the rear side 11 of the folder is the edge 16 of the returned flap 17. Between the edge portion 16 and the flap 17 is the right-angularly extending portion 18. Between the parts 16 and 17 and the intermediate part 18, the flap is scored, as indicated at 19 and 20, to facilitate forming the part 18. When only a comparatively few papers are included in the folder, the flap will be folded only along the crease 19. It will be seen that when papers are placed within the folder, and the flap is bent down so as to overlie the upper edges

of the papers, that is, be positioned between the outermost one of the papers within the folder and the front portion 10, the papers will be snugly confined within the folder and will be prevented from working up and giving the file a mussy appearance or obscuring the filing legend at the upper edge of the folder.

The folder shown in Figure 2 is very similar to that shown in Figure 1, substantially the only difference between the two being that the flange of the returned flap, which is pasted or otherwise secured to the back of the folder, extends upwardly in Figure 2 instead of downwardly as in Figure 1. The folder of Figure 2 consists of the front side 21 and the rear side 22, between which the folder is scored or creased, as indicated at 23 and 24, to facilitate forming the bottom 25 of the folder. Secured to the upper edge 26 of the rear side 22 of the folder is the edge 27 of the returned flap 28. Between the edge 26 and the flap 27 is the right-angularly extending portion 29 between which and the parts 26 and 27 are the creases 30 to facilitate forming the top portion 28 of the folder. The edge 26 of the returned flap, if desired, may be extended and secured to the upwardly projecting filing tab 31, the filing legend being inscribed upon the portion of the edge 26 forming part of the filing tab. In this form of the folder due to the edge 26 being carried up and secured to the upwardly projecting portion of the back 22, the filing tab is of increased rigidity.

Having thus described my invention, what I claim is new and desire to secure by Letters Patent of the United States is:—

1. A folder comprising a blank folded substantially centrally thereof to form a front and a back, and a flap secured to said back adjacent the upper end of said back and projecting outwardly and downwardly forming a bight between said front and back for overlying the contents of the folder, a transverse portion of said back continuing upwardly beyond the bight of said flap and forming a tab.

2. A folder comprising a blank adapted to be folded substantially centrally thereof to form a front and a back, a separate flap arranged to project between said front and said back so as to overlie the contents of said folder, said flap having a strip along

one edge glued to said back adjacent to the upper edge thereof.

3. A folder comprising a blank adapted to be folded substantially centrally thereof to form a front and a back, a tab projecting from the edge of said back, and a flap arranged to project between said front and said back so as to overlie the contents of the folder, said flap having a strip along one edge glued to said back adjacent to the upper edge thereof and formed with a tab corresponding to the first-mentioned tab and secured thereto.

4. A folder comprising a blank adapted to be folded substantially centrally thereof to form a front and a back, a tab projecting from the edge of said back, and a flap formed of a separate strip of material arranged to project between said front and

back so as to overlie the contents of the folder, said flap being firmly secured to said back adjacent to the upper edge thereof and formed with a tab corresponding to the first-mentioned tab and secured thereto.

5. A folder comprising a blank folded substantially centrally thereof to form a front and a back, and a flap secured to said back adjacent the upper end of said back and projecting outwardly and then downwardly between said front and back for overlying the contents of the folder, said outward projection of said flap being spaced a distance below the uppermost edge of the back and the back thereabove forming a support for carrying filing information.

In witness whereof, I hereunto subscribe my name this 9 day of Jan., 1923.

ADOLF H. SCHAFFERT.
